UNITED STATES PATENT OFFICE.

JOHN B. BOURGEOIS, OF WORCESTER, MASSACHUSETTS.

FUSE CUT-OUT.

Application filed May 6, 1926. Serial No. 107,254.

This invention relates to a cut-out for fuses. The principal objects of the invention are to provide for safeguarding household electric apparatus; to provide means whereby fuses carrying a high current cannot be inserted in circuits in such a way as to conduct the electricity, thus necessitating the use of the proper fuses; to provide means whereby the common practice of inserting 5 pennies in the sockets so as to conduct the current without any live fuse will be impossible; to provide means whereby the insertion of any piece of metal will be impossible if the fuse is mounted on a vertical wall; and to improve the construction of the block in which 10 the fuse socket is mounted.

Other objects and advantages of the invention will appear hereinafter.

Reference is to be had to the accompanying 20 drawings in which

Fig. 1 is a central sectional view through a porcelain base having a fuse socket therein constructed in accordance with this invention; and

Fig. 2 is a side view of the fuse block to 25 go with it.

The socket is made in the usual way except for one particular. It is mounted on a single piece of porcelain 10 which is secured in position in any usual way. On this porcelain base there is a conductor 11 at one side and a conductor 12 at the other. These are held down by binding screws 13 and connected with the circuit in the usual way. The porcelain base is provided with a protecting flange 14 as usual in which is located the brass or other metallic conducting socket 15. At the center of this, the porcelain base is rigidly mounted to provide a projection 16 integral 30 with it having a conical hole or depression 17 which is provided at the bottom with a metallic head 18 connected with or constituting a part of one of the conductors 11. The other conductor 12 is connected with the metallic 35 socket 15.

The fuse plug 20 is provided with the usual brass or other metallic screw thread 21 connected with one wire of the circuit and with a central projecting metallic tip 22 at the 40 other. The rest of this plug is of porcelain, hard rubber, or any insulating material. This tip 22 is conical in shape and arranged to fit in the conical depression 17.

When the plug is put into the socket, the 45 projection 22 enters the depression or hole 17 and contacts with the head 18 which is part

of the conductor 11, the screw 21 of course making connection all the time with the conductor 12.

It will be understood that only fuses of 15 60 amperes capacity or smaller will be made with the addition of this tip or projection 22. All fuses of the larger capacity will be made flat on the bottom as is now the case. It is proposed also that fuses of greater capacity 65 than 15 amperes be made with the flat conductor at the end connected with a conductor inside by the use of solder, so that if anyone tries to add a tip to this contact by applying a hot iron he will melt the solder and render 70 the fuse useless.

With this invention ordinary fuse plugs cannot make any contact because they cannot be set down below the top of the projection 16. The use of a penny put across the contact will 75 not result in the conducting of any current for the same reason. The contact cannot be reached by the fingers and if small pieces of nails or other metal are put into the conical hole 17, when the base 10 is mounted on a vertical wall, they will fall out of the recess and cannot be used to conduct the current. In this way the ordinary householder cannot put in a fuse that is of such large capacity that some of his electric apparatus is likely to be 80 85 blown out and he cannot resort to any of the usual subterfuges which are commonly adopted in case there is no fuse at hand.

Although I have illustrated and described only a single form of the invention I am 90 aware of the fact that modifications can be made therein by any person skilled in the art without departing from the scope of the invention as expressed in the claim. Therefore, I do not wish to be limited to all the details of construction herein shown and described, but what I do claim is:—

The combination with a fuse plug having a metallic projection extending beyond its end, with an insulating base having a conducting 100 socket for receiving the plug and having an insulating wall extending across the bottom of the socket and provided with an integral projection extending into the socket and having a perforation therethrough for said projection, and a conductor supported in said base and having a metallic head thereon extending part way up into said perforation, for the purposes described.

In testimony whereof I have hereunto af- 110 fixed my signature.

JOHN B. BOURGEOIS.
